RUBBER HEEL

Charles F. Snyder, Pittsburgh, Pa.

Application December 31, 1938, Serial No. 248,743

1 Claim. (Cl. 36—59)

This invention relates to what are commercially known as rubber heels of a character particularly designed to be attached to leather heels of shoes, boots, and the like.

5 The present invention contemplates a rubber heel having a tread surface provided with one or more portions for taking care of maximum wear to which the heels are subjected to in use, while at the same time providing cooperating means on the tread surface that will afford maximum resistance to slipping when the wearer presses down on the heel tread in the act of walking.

Heretofore, rubber heels have been designed 15 and manufactured primarily for providing a desirable cushion effect and as such have proven highly advantageous, but, so far as I am aware, the tread surfaces thereof have not proven satisfactory for affording resistance to slipping, particularly on wet or icy surfaces.

Among the primary objects of my invention are, to provide a new and improved resilient heel having means on the tread surface for preventing slipping; and to form the tread surface 25 of such character, including ribs and grooves, that the tread surface may be treated, after it has become more or less worn, in a simple manner to restore it to its original efficiency.

In the accompanying drawing, which illustrates 30 applications of my invention:

Fig. 1 is a bottom plan view of a right heel embodying my invention;

Fig. 2, an elevational edge view of the heel;

Fig. 3, a sectional view, the section being 35 taken on the line x—x of Fig. 1; and

Fig. 4, a bottom plan view of a modified form of heel embodying my invention.

Referring to the drawing and first to the form 40 of Figure 1, 5 designates the body of the heel formed of rubber or some suitable resilient composition or material and of any preferred form adapted for application to a heel-lift or a cut-away leather heel of a shoe, boot or the like.

As illustrated and as preferred, the tread surface 45 face is formed with a series of diagonally extending curved ribs 6 and a series of curved continuous grooves 7 separating the ribs. The curvature of the grooves 7 corresponds with the curvature of the ribs, which rib and groove design 50 is such that it may be utilized for forming the tread surface on a heel adapted to be attached to either a right or left shoe or boot.

The side walls of the grooves 7 are slightly 55 inclined as shown by the numeral 8 for the purpose of producing a wedging effect when pressure is applied to the tread surface, thus effectively cooperating with the flat contacting faces of the ribs in resisting slippage.

60 As preferred, the diagonally disposed grooves

and ribs extend from the forward edge or breast 9 of the heel and the forward portion of the outer edge 10 rearwardly and inwardly toward the inner edge 11 thereof, being transversely disposed with respect to a line x—x extending from the front inner corner 12 through the rear outer marginal portion 13 of the said heel. The latter portion 13 is ungrooved and has a flat wear-resisting area extending partially along the rear and outer edges of the heel so as to 10 provide a wear-resisting tread portion at the region of greatest wear, the same being located at the point of initial contact of the heel with the ground in the act of walking.

The portion 13 and a frontal flat portion 14 15 at the inner corner 12 of the heel are located on opposite sides of the groove and rib portion thereof, and serve to stabilize the weight distribution upon the said ribs and grooves, preventing undue deformation thereof while permitting the ribs to properly flex in gripping contact with the ground.

My improved heels may be readily constructed 20 as rights and lefts, with the diagonal disposition of the ribs and grooves being oppositely related on right and left heels. The bottom plan view of Fig. 1 illustrates a right heel.

It will be noted that my improved tread embodies a construction that will permit a ready 25 deepening of the grooves after the rib contacting faces have worn away to some extent, thereby restoring a worn and used heel to its initial efficiency.

In the form of Fig. 4, instead of making the ribs and grooves curved as in the form of Fig. 1 30 the ribs 6a are approximately straight. Likewise, the intervening grooves 7a are diagonally disposed straight or parallel grooves.

In both forms the rubber heels are adapted 35 to be attached to the leather heel by means of 40 nails or other suitable means 15 adapted to be placed in the grooves and then driven home in a convenient manner.

I claim:

A rubber heel for shoes having a tread surface 45 provided with a flat marginal wear-resisting portion located at the outer rear portion of the heel and provided with another flat marginal wear-resisting portion and located at the breast inner corner spaced from the first mentioned 50 wear-resisting portion, diagonally disposed ribs and grooves extending from the breast and outer edge of the heel rearwardly and inwardly toward the inner edge substantially across the tread surface, said ribs and grooves located between the wear portions and covering the balance of the tread surface between the said wear-resisting portions.
